UNITED STATES PATENT OFFICE

2,508,918

POCKET RADIO

Frank T. Hines, Jr., Westwood Village, Calif.

Application November 1, 1946, Serial No. 707,108

2 Claims. (Cl. 250—14)

1

This invention relates to a small pocket radio and receiving apparatus.

The general object of the present invention is to provide a novel form of construction, arrangement and mounting of parts of a radio receiving set by means of which the cost of construction and the space occupied by the receiving set are materially reduced.

In accordance with the present invention, a small, or pocket size, radio receiving apparatus is constructed using the tubes which previously have been designed for hearing aids, together with a type of earphone designed for hearing aid sets. These hearing aid tubes require no socket mounting and are held in position in the apparatus solely by the leads to the tubes. The elements of the receiving apparatus, including the antenna, are all made into a novel assembly which is particularly characterized by the use of a plastic base, on one side of which base a coil serving both for the purpose of an antenna and as a grid inductance is cemented in position, and on the opposite side thereof is mounted, by a supplementary sub-base, various components of the parts, thereby holding the parts rigidly together in operative relationship but occupying a minimum space.

Another feature of the present invention resides in the utility of novel principles of construction in the formation of a simplified and reduced size of variable condenser suitable for controlling the frequency of the receiving apparatus or selecting the station to be received by the apparatus.

Various further features and novelties, objects and advantages of the invention will be apparent from the following description of a preferred form or example of an apparatus embodying the invention. For that purpose I have hereafter described, with reference to the accompanying drawings, a preferred form of the invention, in which

Figure 1 is a side view.

Figure 2 is a similar view, mainly in vertical section.

Figure 3 is a section substantially on the line 3—3 of Fig. 2.

Figure 4 is a section substantially on the line 4—4 of Fig. 2.

Figure 5 is a perspective layout of part of the components.

Figure 6 is an electrical diagram.

Referring, first, to Fig. 6 of the drawings, I have shown the invention as applied to a conventional regenerative type of receiving circuit. 55

2

It is to be understood that many principles of the invention are adaptable to circuits of modified forms of that shown in Fig. 6.

Referring to Fig. 6, 1, 2, and 3 indicate thermionic valves or tubes preferably of the hearing aid type, such, for example, as the Raytheon C. K. 506-AX or the Raytheon C. K. 507-AX, preferably the tube 1 being a 507-AX and the tubes 2 and 3 being 506-AX, or, for lower Fil current, C. K. 503-AX. These tubes are, as illustrated in Fig. 5, small tubes having glass envelopes, the envelopes being compressed at one end, as indicated at 6, and the five lead wires from the tubes extending from the envelope at 6a, as indicated in Fig. 5. These tubes are of sufficiently light weight as to be capable of being firmly suspended in position merely by the strength of the wires forming the leads to the tubes, and thus adapt themselves, as hereafter described, very well to a novel type of assembly used in this present invention.

As a common antenna and grid inductance, there is provided the winding 7 associated with which winding is the feed-back winding 8. These windings are formed into the spider web winding pictorially indicated at 9 in Fig. 5. The main inductance and antenna winding are wound on a plastic plate 10 which is cut along a plurality of spaced apart radial lines 11 to permit the windings to be interwoven through the resilient fingers of plastic material which are attached to the center 12 of the mounting plate. As an illustration, a suitable inductance 7 is formed through the use of about 105 turns of a fine wire, such as No. 36 D. S. C. The inductance 7 may be formed in a thin spider web with none of the windings overlapping and with the longer diameter of the inductance not exceeding 3½ inches. Roughwound on the same plate 10 is the feed-back winding 8, which, for example, may be about 4 turns of the same fine wire.

Preferably the antenna is made as illustrated slightly oblong and the longer ends of both the plastic plate 10 and the windings thereon are curved to conform with the curvature of the case hereafter described. By curving the ends of the antenna winding as illustrated, the directional characteristics are lessened. Without curving the ends of the coil as illustrated, the apparatus would tend to possess considerable directional characteristics, which are generally undesirable in a receiving apparatus of this type.

14 indicates the tuning condenser for the inductance 7 which is shown in perspective in Fig. 5. This condenser is formed by a rather thick

block of plastic 15 into which is threaded a wood screw having a handle member 16. On one face of the block 15 is provided a thin metal plate 17 which is preferably cemented to the block as, for example, by the use of a clear cement. An adjacent plate of thin metal 18 is attached to the rear of the block, as indicated at 19, and bent around over the plate 17, the two plates, however, being separated from each other by insulating material, such as a thin mica plate 20.

The plate 18 is of somewhat resilient metal so that it tends to spring away from the plate 17, thereby reducing the resulting capacity between these plates. The movement of plate 18 towards plate 17 is effected by the wood screw attached to handle 16. Electrical terminals 23 and 24 are provided respectively connected to the plates 17 and 18.

A trimmer condenser may be provided by cementing a small plate 17a on the block 15 at 20 the rear and cutting the plate 18, as indicated at 18a, to form a section movable relative to the plate 17a by an adjustment screw 19a.

I have found that by the construction described I am able to provide a very simple, compact condenser having, however, sufficient variable capacity to cover the entire network broadcast range of stations when used in combination with coils as indicated at 7. Moreover, the condenser permits smooth operation and this entire range of stations is covered with one, or less than one, revolution of the screw 16.

The condenser thus described has a further advantage in that it may be built into the assembly as hereby described merely by cementing the flat block 15 to the base 32.

In the electric diagram of Fig. 6 there are shown coupling resistors 25 and condensers 26 of the usual type; 27 is the grid resistor, 28 the variable screen resistor employed as a volume control; and 30 is the output transformer connected to a hearing aid type of phone 31. In order that these various components may be made into a pocket size radio in a simple and economical manner, there is provided a main base plate 32 which is preferably formed of a plastic material, one which is easily cut or punctured by a heated instrument. At one end of the base plate there is provided an end plate 33 which may be also formed of plastic material and which may be united thereto by a cementing operation. The end plate is provided with three apertures, the center aperture of which would pass the handle 16 of the variable condenser previously described. The condenser rests on the upper face of the plate 32, as shown in Fig. 3, and is cemented thereto. The variable condenser 14 has a knob 34 on the member 16, which knob moves relative to a scale on a dial plate as indicated in Figure 5.

The variable resistor 28, which as previously described in connection with Fig. 6, controls the screen grid potential, is mounted on the end plate 33, and provided with a tightening nut 35 and control knob 36. An "on" and "off" switch, indicated at 37 in Fig. 6, is also mounted on the end plate as indicated at 39.

The three electronic tubes 1, 2 and 3, as illustrated in Fig. 5, are assembled in parallel relation on the base of a trough-shaped subpanel member 40 with the coupling resistors 25 and condensers 26 on the opposite side in the trough provided thereby. The subpanel 40 is then positioned with the coupling resistors in place and with the tubes in place on the main panel 32.

with the trough of the sub-base facing down and the edge 40a resting on an antimicrophonic padding 40b of soft material. In connecting the tubes with the various coupling resistors the lead wires are forced directly through holes in the trough-shaped subpanel member 40 in the manner illustrated whenever it is necessary.

The inductance 7 is then placed against the underside of the plastic base 32, as viewed in Fig. 5 on the opposite side from the subpanel 40. By application of a suitable material, such as by wetting the plastic plates 10 and 32 with methyl methacrylate and pressing them together, the coil is firmly cemented in fixed position to the subpanel. By this manner of assembly a definite spacing is given between these coils and the other elements of the apparatus so that any capacity connections and couplings between the center coil and the remainder of the elements of the apparatus remain fixed in operation.

There is also provided the U-shaped plastic member 41 which is set at the end of the sub-base 32 and used to house the transformer 30. The walls of the member 41 also serve as a partition for dividing the space on the base 32 into separate compartments for receiving the "A" battery, as indicated at 42, and the "B" battery, as indicated at 44.

There is provided a casing 45, open at its two ends, one end being united to the end plate 33 which encloses the sub-base 32 and the parts mounted and supported thereby. There is also provided an outer casing which consists of the metal member 46 which closes the end and provides a common connection for the batteries 42 and 44. The upper portion of the outer case, indicated at 47, should be of some nonmetallic substance, which would not interfere with the reception of the radio signals by the coil 11.

The pocket radio constructed as described is a completely self-contained miniature apparatus, is readily made in size sufficient to fit in a pocket or in ladies small handbags and is complete, including an antenna and batteries. No external connections either of antenna or batteries of any kind are required, and the apparatus may be constructed with the use of minimum parts and minimum weight and minimum costs.

While the particular form of the apparatus herein described is well adapted to carry out the objects and advantages of the present invention, various modifications and changes may be made, and this invention is of the scope set forth in the appended claims.

55 I claim:

1. A radio receiving apparatus which includes a plurality of resistively coupled multi-electrode tubes and a generally flat wound inductance, a plastic mounting plate against one side of which said flat inductance is positioned and cemented, and on the other side of which said tube resistances are assembled, there being provided a supplemental trough-like mounting member with the trough of said member faced down against said main mounting plate and enclosing the resistances coupling said tubes, the tubes being mounted on the opposite side of said supplemental mounting member, said tubes laying with their sides against the face of said supplemental mounting member and being held in position solely by wiring leading to the elements of said tubes, which wiring extends through openings in said supplemental member to said resistors.

75 2. A radio receiving apparatus which includes

a plurality of resistively coupled multi-electrode tubes and a generally flat wound input inductance, a plastic mounting plate against one side of which said flat inductance is positioned and cemented, and on the other side of which said tube resistances are assembled, there being provided a supplemental trough-like mounting member with the trough of said member faced down against said main mounting plate and enclosing the resistances coupling said tubes, the tubes being mounted on the opposite side of said supplemental face member, the tubes laying in flat parallel relation against the supplemental member and being held in position solely by the wiring extending between the tubes.
